Inventor:
Fred M. Young.
By Kummer & Tetzlaff,
Milw.

UNITED STATES PATENT OFFICE.

FRED M. YOUNG, OF RACINE, WISCONSIN.

REENFORCEMENT FOR TUBULAR RADIATORS.

Application filed March 21, 1927. Serial No. 177,085.

This invention relates to heat interchangers of the type usually employed as radiators for cooling internal combustion engines.

The main objects of this invention are to 5 provide improved reenforcing means for securing heat interchanger headers to their cores and more particularly to provide improved means for securing the core of an automobile radiator to its upper and lower 10 header sheet and tank, and obviate much of the leakage resulting from the strain of weaving, twisting, road shocks and vibration.

An illustrative embodiment of the invention is shown in the accompanying drawings, 15 wherein,—

Fig. 1 is a fragmentary front elevation of an automobile radiator core and its bottom tank;

Fig. 2 is a plan view of the radiator structure and its water tubes, taken on the line 20 2-2 of Fig. 1 and showing the reenforcing pieces for securing together the core and header;

Fig. 3 is a fragmentary end elevation of an 25 automobile radiator core and its bottom header, partly in section; and

Fig. 4 is a perspective detail.

It is generally known that the strain of 30 weaving, twisting and vibration of automobile radiators due to road travel, frequently causes the soldered joints of radiator tubes to break and spring leaks. To minimize this trouble the present invention utilizes some of the tubes of the core, preferably those at the 35 sides of the radiator, as braces, securely fastened to the top and bottom tanks.

In the construction shown, the lower header or water tank 1 is apertured to receive the vertically disposed water tubes 2 which are 40 supported by the fins 3 of the core section. The tubes 4 at the outer edges of the core are made shorter than the remaining tubes and are provided with plugs 6 in their ends having large flanges which are soldered to 45 the tube header sheets and thus serve as re-enforcing columns. These plugs practically fill the ends of the tubes and are soldered in place, being preferably provided with a transverse sweating hole 5 for the solder to run through. When the tubes are of flattened sectional form, as in the drawings, these plugs or reenforcing pieces may be made of metal strips by bending their middle portions upon 50 themselves to form a shank 7, and by bending

their end portions in opposite directions to 55 form a head or flange 8.

A large soldering surface between the sides and ends of the shank and the interior of the tube is thus provided. Added reenforcing strength is provided by the solder running 60 through the sweating holes. The head 8 of the reenforcing piece is soldered to the header plate and its comparatively large surface insures joint strength of the radiator structure. The header plate is preferably depressed 65 to receive the flange of the reenforcing plate, thus insuring that the solder will run around the edges of the flange and strengthen the joint.

It will thus be seen that the use of re-enforcing pieces adds considerable strength to that part of the radiator structure most susceptible to breaking by the twisting, weaving, and vibration of road shocks during the 70 travel of the automobile, and that leakage is 75 thereby practically prevented.

While but one specific embodiment of this invention has been herein shown and described, it will be understood that numerous details of the construction shown may be 80 altered or omitted, without departing from the spirit of this invention, as defined by the following claims.

I claim:

1. In a heat interchanger having a header and a multi-tubular core, certain of the tubes being non-communicating with the header and provided with sweat apertures near their extremities, means for securing the header and the core section together including T-shaped members whose shanks are provided with sweat apertures which register with the sweat apertures in the noncommunicating tubes when inserted and secured within such tubes as by solder and whose heads are secured to the header. 85 90 95

2. In a heat interchanger having a header and core section having flattened tubes, means for securing the header and core section together including depressed portions on the header plate and solid T-shaped reenforcing plugs having shanks inserted and secured within certain of said flattened tubes, and flush fitting flanged heads secured within and substantially filling said depressed portions. 100 105

Signed at Racine this 14th day of March, 1927.

FRED M. YOUNG.
